ELECTRICALLY CONTROLLED STOP-MOTION SYSTEM

Frank A. Hayes, Middletown, N. J., assignor to
The Singer Manufacturing Company, Elizabeth, N. J., a corporation of New Jersey

Application June 29, 1949, Serial No. 101,943

6 Claims. (Cl. 112—219)

1

This invention relates to a control system and more particularly to a motor control system for driving a machine which performs a predetermined work cycle and comes to rest with a positive stop.

One of the objects of this invention is to provide a control system for the stop-motion of a group-stitch sewing machine having a direct-connected driving motor, which system shall insure that the latch holding the stop-motion lever in the run position is engaged before the motor can be started.

Another object of this invention is to provide a control system for the stop-motion of a group-stitch sewing machine, which system shall provide just sufficient rotational energy at the stop position to impart to the stop motion lever the energy necessary to operate a trimmer knife or any other auxiliary device that may be desirable.

A still further object of this invention is to provide a stop motion control for a machine having a predetermined operating cycle including starting, high speed running, low speed running, and stopping, without the use of mechanical speed-change devices and/or clutches.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings, Fig. 1 is a side elevation of a sewing machine embodying the invention.

Fig. 2 is a top plan view, partially in section taken on the line 2—2 of Fig. 1.

Fig. 3 is a schematic wiring diagram of a motor control system embodying the invention.

Fig. 4 is a detail of elements of the machine of Fig. 1.

Fig. 5 is a modification of part of the system of Fig. 3.

Referring to Fig. 1, the machine is constructed with a frame comprising a cylinder bed or work arm 1 from which rises the standard 2 carrying a bracket-arm 3 terminating in a hollow head 4. Journaled within and longitudinally of the arm 3 is the main-shaft 5 from which is derived, through usual operative connections, the reciprocating movements of the needle-bar 6 carrying the needle 7. In practice, the needle 7 cooperates with a suitable loop-taker, not shown, within the free end of the hollow cylinder-bed 1.

2

The work is adapted to be clamped between the upper and lower members of a work-holder 8 which, in the particular embodiment illustrated, is moved to and fro over the work-support to distribute the stitches in accordance with the desired pattern. The present work holder is of the general type disclosed in the patent to Barron, No. 1,205,317, of November 21, 1916, and means for imparting longitudinal and lateral movements to the work-holder 8 is fully described in the patent to Horton, No. 1,051,998, of February 4, 1913.

The stop-motion device comprises a pivoted stop-motion lever 9 which carries a spring-pressed plunger-rod 10 adapted to engage the stopping cam 11 fixed to the main shaft 5 in performing the stopping operation. The main shaft 5 carries a driving pulley 12 for belt connection to an electric motor as will be explained presently. The plunger rod 10 is held out of operative relation with said cam by means of a spring-pressed latch lever 13, one end of which is provided with a hook 14 adapted to engage a notch 15 upon the stop lever 9 to maintain the same in inoperative position in opposition to a spring 16. The other end of the latch-lever 13 lies in the path of movement of the tripping lug 17 secured adjustably upon the inner face of a cam wheel 18. This stop-motion device is of the same general type as that shown and described in the aforesaid U. S. patent to Horton, No. 1,051,998 of February 4, 1913, to which reference may be had for a more complete description thereof. It will be understood that, by pulling down on chain 19, an angle lever 20, pivoted at 21, causes the stop lever 9 to move carrying the plunger-rod 10 out of engagement with the stopping cam 11, and in this position the machine is ready to operate.

The above description refers to a conventional group-stitch sewing machine. There will now be described certain electrical control equipment in its relation to certain mechanical elements of the machine. To facilitate an understanding of this structure, reference will be made to the schematic diagram of Fig. 3 wherein 22 and 23 indicate, respectively, the polyphase and single-phase primary windings of an electrical induction motor of the two-speed type shown and described in the U. S. Patent No. 2,510,468 of Harry B. Fuge, filed September 8, 1948. The rotor of this motor is permanently connected by a belt (not shown) to the pulley 12 to rotate the main-shaft 5 of the sewing machine. A switch S1 is mounted on a plate 24 secured to the machine frame and is operatively connected to a depending portion 25

of the stop lever 9 so that contacts 26 thereof are closed in the "run" position of the stop lever and are open in the "stop" position of said lever.

A switch S2, also mounted on the plate 24, is operatively connected to the outer cam surface 27 of the cam wheel 18. The arrangement is such that when a notched portion 28 of the cam surface is in engagement with the switch follower 29, contacts 30 and 31 are in engagement. At all other times, contact 31 is in engagement with contact 32. A third switch S3 is mounted on a plate 33 secured to the machine frame and is operatively connected to the latch lever 13 so that normally, with the stop lever 9 latched in the "run" position, contacts 34 are made. When the latch 13 is tripped by the lug 17, contacts 34 open.

A source of polyphase alternating current energy is indicated by L1, L2, L3. A contactor 35 having an operating coil 36, normally open contacts 37, 38, 39 and normally closed contacts 40, 20 controls the flow of current to the motor windings 22 and 23. A second contactor 41, having an operating coil 42 and normally open contacts 43 and 44 is also employed to control the flow of current to the motor windings as will be explained presently.

In order to simplify the schematic diagram, it has been necessary to show the stop cam 11 located on the opposite side of the stop lever 9 from its actual position as shown in Fig. 1 but this in no sense alters the operation of the system.

Operation

The schematic diagram of Fig. 3 represents conditions just after the stop motion lever 9 has been thrown to the "run" position by pulling down on the chain 19. The latch lever 13 holds the stop motion lever 9 in the "run" position as shown. Contacts 26 of switch S1, contacts 34 of switch S3 and contacts 31, 32 of switch S2 are closed. A circuit is completed from L1 through contacts 34 of switch S3, contacts 26 of switch S1, contacts 31, 32 of switch S2, the normally closed contacts 40 of the contactor 35, thence through the operating coil 42 of the contactor 41 to L2. 45 This puts voltage on the coil 42, and contactor 41 operates to close contacts 43 and 44 thus connecting the windings 22 to L1 and L3; L2 being permanently connected to said windings. The motor thus comes up to speed and runs as a polyphase induction motor at a speed determined by the number of poles of the winding and the frequency of the supply. This represents the high speed connection, and the cam wheel 18 is driven in the direction of the arrow and imparts to the work-holder 8 the desired motions as clearly set forth in the aforementioned Horton Patent No. 1,051,998.

As the end of the stitching cycle is approached, the follower 29 of the switch S2 drops into the notched portion 28 of the cam surface 27, thus opening the contacts 31, 32 and closing the contacts 30, 31. This opens the circuit to the coil 42; contactor 41 operates to open contacts 43 and 44 to remove voltage from the motor windings 22. 60 At the same time, the following circuit is completed; from L1 through contacts 34 of the switch S3, contacts 26 of the switch S1, contacts 31, 30 of the switch S2, thence through the coil 36 of the contactor 35 to L2. This puts voltage on the coil 36 and the contactor 35 operates to open contacts 40 and to close contacts 37, 38 and 39. Voltage from L1—L2 is thus applied to the low-speed winding 23 of the motor which is thus braked to and run at low speed as is clearly set forth in 75

the aforementioned patent application, Serial No. 48,214. Concurrently, a short-circuit is provided around the contacts 34 of the switch S3 by closed contacts 39, and around the contacts 30, 31 of the switch S2 by closed contacts 37. This provides that the switch S1, alone, is available for controlling the operation of the contactor 35 to remove voltage from the motor when the stop motion lever 9 is released to stop position, and insures that the motor torque is available to drive the machine at least within one shaft revolution of positive stop position, which would not be the case if, for example, the operation of the switch S3 were allowed to determine the operation of the contactor 35.

Further movement of the cam wheel 18 causes the lug 17 to engage one end of the latch 13, thus releasing the stop motion lever 9, which is immediately urged into "stop" position by the spring 16. The contacts 34 of switch S3 are opened, but this has no electrical effect because said contacts are shorted out by the contacts 39 as explained. The follower 29 of the switch S2 rides up out of the notched portion 28 and opens the contacts 30, 31 and closes the contacts 31, 32. This, too, has no electrical effect because contacts 30, 31 are shorted out by the contacts 37 as explained. Finally, the stop motion lever 9 moves into "stop" position, having been released by the latch lever 13. Switch S1 opens, removes voltage from the operating coil 36 and operates the contactor 35 to open contacts 38, thus removing voltage from the low-speed winding 23, by which time the motor is held stationary by the positive stop of the machine.

It will be observed that the circuit is such that the switch S3, operated by the latch lever 13 actually controls the starting of the motor. Thus the hook 14 must fully engage the notch 15 before the switch S3 can close its contacts 34 to energize the motor windings. This insures that the stop-motion lever 9 must be fully latched to its "run" position before the driving torque can be applied by the motor. However, in disconnecting the motor from the supply source at the end of the stitching cycle, it is the switch S1 which governs, and not the switch S3. This shift of switch control is effected because it is desirable to have the motor drive the machine right up to the positive stop position or as near thereto as is practicable so that sufficient rotational energy will be available to operate trimmers or perform any operation necessary at the end of the stitching cycle.

Fig. 5 shows a contactor 45 which may be used 55 in substitution for the contactor 35 when it is desired to eliminate the switch S1 from the circuit. The connections are the same as before except that S1 has been eliminated and the lead marked "To S3" goes directly to S3 instead of going through the switch S1 as before. The operation is the same as explained above except that the switch S3, operated from the latch lever 13, controls the disconnection of the motor winding 23 at the end of the stitching cycle. Thus, under these conditions, the motor will be turned off sooner than when the switch S1 governs and less rotational energy is required to be absorbed when the positive stop is reached. This modification finds application in those cases in which operation of auxiliary devices at the end of the stitching cycle are not necessary.

Having thus set forth the nature of the invention, what I claim herein is:

1. In a stop-motion system, a machine having an operating shaft, a timing cam connected to

said shaft for determining a sequence of operations for said machine, a stop cam carried by said operating shaft, a stop lever spring-biased to engage said stop cam to positively stop said machine in a predetermined shaft position, means for moving said stop lever out of engagement with said stop cam, latch means for holding said stop lever in said out-of-engagement position, means positioned on said timing cam for operating said latch to release said stop lever, an electric motor permanently and drivingly connected to said machine, a source of electrical energy, said motor having selectively a high-speed connection and a low-speed connection with said source of energy, a first contactor for establishing said high-speed connection, a second contactor for establishing said low-speed connection, and control means for said contactors, comprising a first switch operated by said stop lever, a second switch operated by said latch means, and a third switch operated by said timing cam, said switches being operable in sequence to start and run the machine at high speed, to transfer to slow speed, and finally to stop the machine positively in a predetermined shaft position.

2. In a sewing machine adapted to perform a definite series of operations, stitch forming mechanism including a reciprocating needle, a shiftable work-holder, a cam for controlling the shifting movements of said work holder, a stop-motion lever biased to a stop position, a latch lever for holding said stop-motion lever out of said stop position, an electric motor operatively connected to said sewing machine, said motor having two separate primary windings, contactor means for controlling the selective excitation of said windings, and separate switch means operatively responsive to the movements, respectively, of said stop motion lever, said cam, and said latch lever, for controlling the operation of said contactors to select the driving condition for said sewing machine in timed relation with said definite series of operations.

3. In a group-stitch sewing machine, a cam wheel driven by said machine for timing the performance of a definite series of stitching operations, a two-speed motor permanently connected to said sewing machine to drive same, contactors for controlling the starting, the stopping and the speed of said motor, a stop-motion lever, and a latch lever therefor, switch means for controlling said contactors responsive, respectively, to the movement of each of said cam wheel, said stop-motion lever, and said latch lever, said latch lever operated switch being arranged so that the latch must engage the stop-motion lever before the switch can operate.

4. In a sewing machine adapted to perform a definite series of operations, a cam for controlling the cycle of operation of the sewing machine, a two-speed electric motor directly connected to

said sewing machine, control means for starting and stopping said motor, and for selecting the speed thereof, said control means including switches operated in timed relation with said cycle of operation, a manually controlled starting lever and a latch for said lever, one of said switches being operated by said latch so that the starting lever must be latched in before said switch operates.

5. An electrically-controlled stop-motion system for a sewing machine, comprising a cam operated by said sewing machine for controlling a cycle of sewing operations, a two speed electric motor having a high-speed winding and a separate low-speed winding and drivingly connected to said sewing machine, a stop-motion lever adapted to be operated to stop said sewing machine in a predetermined shaft position, a latch for securing said stop-motion lever in its non-stop position, means for controlling said motor, including switches operated in timed relation to the cycle of sewing operations, one of said switches being operated by said stop-motion lever to disconnect said low-speed motor winding from a source of power, and another of said switches being operated by said high-speed latch to connect said motor winding to the source of power.

6. In an electrically controlled stop-motion system for a group stitch sewing machine, an operating shaft, a timing cam driven by said shaft for determining a sequence of stitching operations for said sewing machine, a stop cam carried by said operating shaft, a stop lever normally biased for engagement by said stop cam to positively stop said machine in a predetermined shaft position, means for moving said stop lever out of engagement with said stop cam, latch means for holding said stop lever in said out-of-engagement position, means operated by said timing cam for releasing said latch, a two-speed electric motor permanently and drivingly connected to said sewing machine, a source of electrical energy, a first switch operated by said latch means for controlling the connection of said motor to said source of energy for operation at high-speed, a second switch operated by said timing cam for controlling the connection of said motor to said source of energy for braking to and operation at low-speed, and a third switch operated by said stop lever to disconnect said motor from said source of energy to stop said motor.
